BOAT

Thomas Currie, High Meadow Road, Southport, Conn.

Filed Feb. 3, 1960, Ser. No. 59,249

Term of patent 7 years

(Cl. D71—1)

FIG. 1

FIG. 2

FIG. 3

FIG. 4

Fig. 1 is a perspective view of a boat showing my design;

Fig. 2 is a side elevational view thereof;

Fig. 3 is a front elevation of the boat; and

Fig. 4 is a rear elevation thereof.

I claim:

The ornamental design for a boat, substantially as shown.
